UNITED STATES PATENT OFFICE.

JOSEPH F. RUSSELL, OF OAKLAND, CALIFORNIA, ASSIGNOR TO JOHNSON WASHER COMPANY, OF OAKLAND, CALIFORNIA, A CORPORATION OF CALIFORNIA.

CLOTHES WRINGER.

Application filed May 4, 1925. Serial No. 27,630.

This invention relates to clothes wringers and particularly to domestic power driven wringers of the reversible type.

A considerable number of power driven clothes wringers for domestic use are being manufactured and sold and while they are fairly simple to manipulate from a mechanical point of view and are also efficient in operation they meet with one common objection; that is, clothing will sometimes become accidentally wrapped about the wringer rolls and the clothes usually become ripped or torn before the operator has time to disconnect the drive or shut off the power.

The object of the present invention is to generally improve and simplify the construction and operation of wringers of the character described and particularly to overcome the objection above referred to, to provide a wringer in which the wringer rolls are maintained in yielding contact with relation to each other by spring tension, to provide means whereby the spring tension on the rolls may be either automatically or manually released if clothing becomes accidentally wrapped about the rolls, and further to provide an automatic or manual release which may be operated from either side of the wringer, this feature being of particular importance as the wringer is reversible and the operator may therefore stand on either side of the wringer and manually release the spring tension mechanism when required.

One form which my invention may assume is exemplified in the following description and illustrated in the accompanying drawings, in which—

Fig. 1 is a side elevation of the wringer.

Fig. 2 is a plan view partially in section.

Fig. 3 is an end view.

Referring to the drawings in detail and particularly to Fig. 1, A indicates in general a clothes wringer consisting of a main frame B in which is journalled a pair of horizontally disposed wringer rolls 2 and 3. The frame beam is attached to a housing generally indicated at C. This housing encloses a driving mechanism consisting of a driving shaft 4, a driven shaft 5 to which the lower wringer roll 2 is attached, a pair of bevel gears 6 and 7, and a driving bevel gear 8. The gears 6 and 7 are loosely mounted on the driven shaft and they are both provided with clutch faces as shown at 9. A

clutch member 10 is splined on the shaft and is adapted to be thrown into engagement with one or another of the cooperating clutches carried by the gears 6 and 7. When engagement is made with the clutch on the gear 7 the rolls 2 and 3 are driven in one direction, for instance—ahead, and if the clutch is thrown into engagement with the gear 6 and its cooperating clutch a reverse drive is transmitted. Gears 6 and 7 remain in constant mesh with the driving gear 8 and the drive is transmitted through the clutch member 10 to the driven shaft as the clutch member is splined thereto. A shifting lever 11 is employed whereby the clutch 10 may be manually thrown into engagement with the respective cooperating clutches or may be moved to a neutral position as shown in Fig. 1. The housing C together with the main wringer frame B attached thereto is turnably mounted on the upper end of a vertically disposed bearing tube or stationary post 12 which may be a fixed part of a domestic clothes washing machine. The driving shaft 4 extending through the tube may derive its power from any source desired or may be driven as an auxiliary to the mechanism of the washing machine to which it is connected. This feature does not form any part of the present mechanism and illustration thereof is thought unnecessary.

The main feature of the present invention is the provision of means for maintaining the wringing rolls 2 and 3 in yielding contact with relation to each other by means of spring tension, and to provide means for automatically or manually releasing the spring tension on the rolls if clothing becomes accidentally wrapped about the same. To clearly illustrate this feature, reference will be particularly made to Figs. 2 and 3. The main frame B is provided with end frame sections generally indicated at D and F. Slidably mounted in the end frame section F is a pair of superposed bearing members 14 and 15. These bearings are substantially square in shape when viewed from the end as shown in Fig. 3 and they are free to move in a vertical direction within guide grooves formed in the end frame F. Each bearing member carries an anti-friction bearing consisting of a plurality of ball bearings 16 which surround and support a bushing 17. A shaft 18 carries the lower roll and this

shaft is extended and connected with the driven shaft 5 so that it will be continuously rotated in one direction or another through the gear transmission illustrated by the gears 6, 7, and 8. The upper bearing member 15 is similarly provided with anti-friction bearings and a bearing bushing which is supported thereby, and the wringer roll 3 is secured to a shaft 19 which is journaled therein. The upper wringer roll 3 will accordingly rest by gravity on the lower wringer roll and as the weight of the upper roll is not sufficient to properly wring the clothes it is obvious that pressure must be exerted on the upper roll to produce the proper action. This is accomplished as follows: Formed on one side of the end lug F is an outwardly projecting flange 20. This lug has a cored or drilled opening formed therein through which a bolt 21 extends. The lower end of the bolt is threaded and provided with an adjusting nut 22. A helical spring is interposed between the nut and the under side of the lug 20 as shown at 23 and a combination spring tensioning and releasing lever is pivotally connected with the upper end of the bolt at the point indicated at 23^a. The lever proper is nothing more or less than an elongated plate such as shown at 24. It is forked at one end as shown at 25 to permit the upper end of the bolt or rod 21 to pass therethrough. A pin 23^a is passed through the upper end of the rod and the forked member 25 and a pivotal connection is in this manner formed. The lower faces of the forked members 25 are cam shaped as shown at 26 and it is accordingly possible to increase and decrease the tension of spring 23 by swinging the lever about the pivotal point 23^a. The opposite end of the lever is slotted as at 27 and a latching lever 28 is adapted to pass therethrough to secure the lever in the horizontal position shown in Fig. 3. The latching lever may be manually released or automatically released as hereinafter described. Formed on the under side of the lever 24, approximately centrally thereof, is a central rib or projection 30. This rib engages the upper bearing member 15 and as such exerts a downward pressure on the bearing and the shaft and rollers supported thereby. This tension may be increased or decreased by merely adjusting the position of the nut 22. The end frame D is identical in construction with the end frame F; that is, it is provided with bearing members 14 and 15 to support the shafts 18 and 19, it is provided with a lever such as shown at 24, a locking latch 28, and a bolt and spring such as shown at 23 to exert a downward pressure on the lever 24 and the bearing member engaged thereby. The only difference between the mechanism disposed in the end frame F and in the frame D is that one is reversed with relation to the other. By referring to Fig. 2 it will be noted that the spring 23 and the fulcrum point for the lever 24 carried by the frame D is disposed on one side of the wringer rolls and the spring 23 and fulcrum point for the lever 24 are disposed on the opposite side on frame F. This is of material importance as the wringer is reversible and it is thus possible for the operator to release the spring tension on the rolls when standing either on one side or the other by merely manually tripping the locking latch 28. For the purpose of automatically releasing the spring tension, or, in other words, releasing the locking latches 28 at one end of the frame or the other, a pair of guide plates 40 and 41 are employed. These plates extend substantially from end to end of the wringer rolls and they are provided with upwardly extending end sections 42 which are pivotally mounted in the end frames as indicated at 43. One end plate 42 is extended to form the locking latch 28 and the other end plate on the opposite side is also extended to form a locking latch 28, this being necessary to permit reversal of the springs 23 and the releasing levers 24. The guide plates serve two functions. First, that of directing the clothing inwardly between the rollers when wringing the same, and, secondly, that of automatically releasing the spring tension upon the rolls if clothing should become accidentally wrapped about the same. This operation is accomplished as follows: By referring to Fig. 3 it will be noted that the inner edges of the guiding plates 40 and 41 assume a position where they substantially contact with the lower wringer roll 2, hence if clothing should become accidentally wrapped about the lower wringer roll it can readily be seen that the increased diameter of the roll caused by the wrapping of the clothing thereabout would cause the clothing to engage the inner edges of the guide plates 40 and 41. They would consequently be forced outwardly away from the rolls and as such would swing about the fulcrum points 23^a. The locking latches 28 will then spring inwardly and release the levers 24. Danger of ripping or tearing the clothing will thus be obviated as all pressure is released and the operator will at the same time be warned as the sudden release of one or both of the levers 24 would cause sufficient noise to attract the operator's attention. It might be stated that actual experience has proven that only one end of the upper wringer roll is usually released when clothing becomes wrapped about the lower roll. For instance, if the lower wringer roll is rotating in one direction and the clothing starts to wrap around the same the greatest thickness will be assumed on the side which is engaged by the guide plate 41. This will thus first be forced outwardly and the connected lever 24 will be released. If the clothing should continue to wrap before the operator would have a chance to disconnect the

drive or shut off the power, the second guide plate would be engaged and swung outwardly and both ends of the upper roll would be released. The upper roll could then be removed, if desired, to facilitate unwrapping of the clothing from about the lower roll, and in fact the lower roll could also be removed if desired as both bearings shown at 14 and 15 are freely movable in the end frames

10 D and F.

The mechanism as a whole is simple and substantial in construction and simple to operate. The housewife or other individual operating the wringer may stand on either side 15 of the same and may manually release the spring tension on the rolls from either side. The wringer mechanism is furthermore provided with means for automatically releasing the spring tension and danger of ripping or 20 tearing the clothing is therefore entirely obviated.

While certain features of the present invention are more or less specifically illustrated, I wish it understood that various 25 changes in form and proportion may be resorted to within the scope of the appended claims. I similarly wish it understood that the materials and finish of the several parts employed may be such as the experience and 30 judgment of the manufacturer may dictate or various uses may demand.

Having thus described my invention, what I claim and desire to secure by Letters Patent is—

35 1. A wringer comprising a frame, a pair of wringer rolls journaled therein, spring pressure means for maintaining the rolls in yielding contact with relation to each other, a guide plate disposed on one side of the wringer rolls to direct clothing inwardly between the rolls, means for permitting movement of said guide plate if clothing becomes accidentally wrapped about the wringer rolls, and means actuated by movement of said 45 plate for releasing the spring pressure on one end of the rolls.

2. A wringer comprising a frame, a pair of wringer rolls journaled therein, a pair of pressure actuated members maintaining the 50 rolls in yielding contact with each other, a pivotally mounted guide plate disposed on one side of the wringer rolls to direct clothing inwardly between the rolls, said plate adapted to swing about its pivot if clothing becomes accidentally wrapped about the wringer rolls, and means actuated by pivotal movement of the guide plate for releasing pressure on one end of the wringer rolls.

3. A wringer comprising a main frame 60 having a pair of spaced end frames formed thereon, a pair of lower bearing members in the end frames, a driving shaft journaled therein and carrying a wringer roll, a pair of upper bearing members, one in each end frame, a shaft journaled therein and carrying an upper wringer roll, means permitting

free vertical movement of said last named bearing members, a pivotally mounted lever on one of the end frames, said lever being engageable with the adjacent bearing of the upper wringer roll to exert a downward 70 pressure thereon, spring means engageable with one end of said lever to exert a constant downward pressure on the lever and the upper bearing member with which it engages, and a locking latch engaging the 75 opposite end of said lever to retain said lever in engagement with the upper bearing member.

4. A wringer comprising a main frame having a pair of spaced end frames formed thereon, a pair of lower bearing members in the end frames, a driving shaft journaled therein and carrying a wringer roll, a pair of upper bearing members, one in each end frame, a shaft journaled therein and carrying an upper wringer roll, means permitting free vertical movement of said last named bearing members, a pivotally mounted lever on one of the end frames, said lever being engageable with the adjacent bearing of the upper wringer roll to exert a downward 80 pressure thereon, spring means engageable with one end of said lever to exert a constant downward pressure on the lever and the upper bearing member with which it engages, a locking latch engaging the opposite 85 end of said lever to retain said lever in engagement with the upper bearing member, and means whereby the locking latch and the lever is automatically released if clothing 90 becomes accidentally wrapped about the wringer rolls.

5. A wringer comprising a main frame having a pair of spaced end frames formed thereon, a pair of lower bearing members in the end frames, a driving shaft journaled therein and carrying a wringer roll, a pair of upper bearing members, one in each end frame, a shaft journaled therein and carrying an upper wringer roll, means permitting free vertical movement of said last named bearing members, a pivotally mounted lever on one of the end frames, said lever being engageable with the adjacent bearing of the upper wringer roll to exert a downward 100 pressure thereon, spring means engageable with one end of said lever to exert a constant downward pressure on the lever and the upper bearing member with which it engages, a locking latch engaging the opposite 105 end of said lever to retain said lever in engagement with the upper bearing member, and means whereby the locking latch and the lever is automatically released if clothing 110 becomes accidentally wrapped about the wringer rolls.

115 6. A wringer comprising a main frame having a pair of spaced end frames formed thereon, a pair of lower bearing members in the end frames, a driving shaft journaled therein and carrying a wringer roll, a pair of upper bearing members, one in each end frame, a shaft journaled therein and carrying an upper wringer roll, means permitting free vertical movement of said last named bearing members, a pivotally mounted lever on one of the end frames, said lever being engageable with the adjacent bearing of the upper wringer roll to exert a downward 120 pressure thereon, spring means engageable with one end of said lever to exert a constant downward pressure on the lever and the upper bearing member with which it engages, a locking latch engaging the opposite 125 end of said lever to retain said lever in engagement with the upper bearing member, a guide plate pivotally mounted on the main frame on one side of the wringer rolls and adapted to direct clothing inwardly between the wringer rolls, said plate adapted to swing about its pivotal mounting if clothing becomes accidentally wrapped about the wringer rolls, and means whereby pivotal movement of the guide plate is transmitted

to release the locking latch and the lever co-operating therewith.

6. A wringer comprising a main frame having a pair of spaced end frames formed thereon, a pair of lower bearing members mounted in the end frames, a driving shaft journaled therein and carrying a lower wringer roll, a pair of upper bearing members, one in each end frame, said bearing members being vertically movable in the end frames, a shaft journaled in said bearings and carrying an upper wringer roll, a pivotally mounted lever on one end frame, one end of said lever being engageable with the adjacent upper bearing member to exert a downward pressure on said bearing member and the upper wringer roll carried thereby, a cam member at one end of the lever, a downwardly projecting bolt connected to said cam and off-center with relation there-

to, a spring engageable with the bolt intending to rock the lever about its cam to assume a vertical position, a locking latch engageable with the opposite end of the lever and securing the lever in a position where it will exert a downward pressure on the upper bearing member and the wringer roll journaled therein, a guide plate pivotally mounted on one side of the main frame and adapted to direct clothing inwardly between the rolls, said pivotal mounting permitting outward swinging movement of the guide plate if clothing becomes accidentally wrapped about the wringer rolls, and means whereby outward movement of the guide plate about its pivots is transmitted to release the locking latch and the lever engaged thereby to relieve the wringer roll of spring pressure.

JOSEPH F. RUSSELL.
